UNITED STATES PATENT OFFICE.

JAMES F. SPALDING, OF KANSAS CITY, MISSOURI.

FIRE-ESCAPE LADDER.

1,190,334.

Specification of Letters Patent. Patented July 11, 1916.

Application filed April 8, 1915. Serial No. 19,910.

To all whom it may concern:

Be it known that I, JAMES F. SPALDING, a citizen of the United States, residing at Kansas City, in the county of Jackson and 5 State of Missouri, have invented certain new and useful Improvements in Fire-Escape Ladders, of which the following is a specification.

My invention relates to improvements in 10 portable fire escapes and my object is to provide an efficient apparatus of this character which can be carried around in a suit case, or other receptacle, by travelers for use in hotels and other buildings not properly 15 equipped with fire escapes.

The present invention relates more particularly to a holder which may be quickly adjusted to any size window sill for the purpose of suspending therefrom my fire 20 escape ladder.

In order that the invention may be fully understood, reference will now be made to the accompanying drawings, in which:

Figure 1 is a perspective view of my fire 25 escape suspended from the window of a building, ready for use. Fig. 2 is a broken vertical section of the building with the fire escape suspended from a window thereof. Fig. 3 is a plan view of a holder forming 30 an important feature of the invention. Fig. 4 is a section on line IV—IV of Fig. 3, with the addition of the upper portion of a window sill to which the holder is secured. Fig. 5 is a section on line V—V of Fig. 3, 35 with the addition of the upper portion of the window sill. Fig. 6 is an inverted plan view of the holder.

A designates a portion of a building, B two windows thereof, and C a window sill 40 from which my fire escape is adapted to be suspended. Said fire escape embodies a flexible ladder 1, which is held away from the wall of the building by a bracket 2, as disclosed by Figs. 1 and 2. As the ladder 1 45 and the bracket 2 are in all substantial respects like those disclosed in my copending application Serial No. 19,909, further description thereof is deemed unnecessary.

Referring now to the important feature 50 of the present invention, 3 designates a holder which is adapted to grip the upper portion of the window sill C and reliably support the ladder 1 therefrom. Said holder embodies a bar 4 rigidly connected at its 55 ends to a pair of claw members 5, which extend over the top of the window sill C and

have their front ends bent into L-form 6 to pass downward and backward to engage the underside of the top piece of said window sill C, as disclosed more clearly by Fig. 4. 60

The L-shaped hooks 5 are provided with thumb screws 7, adapted to bear upon the upper surface of the window sill C and force the pointed terminals 8 of said claw members into the underside of said window sill 65 stool, so that there will be no danger of the hooks 5 losing their hold when subjected to the weight of a person descending the ladder 1. The upper horizontal portions of the hooks 5 are supported a slight distance 70 above the top of the window sill C, by the thumb screws 7 and spherical feet 9. This arrangement raises the bar 4 above the top of the sill C high enough to permit a person to obtain a firm grip upon a rung 10, constituting a part of the holder 3. The rear ends of the hooks 5 are provided with pivoted 75 eyes 11 to engage with snap hooks 12 at the upper ends of the ladder 1.

The rung 10 is rigidly secured at its ends 80 in the annular terminals 13 of a pair of hooks 14, adapted to coact with the hooks 5 in reliably securing the holder 3 to the window sill C. The rung 10 is reliably held in the terminals 13 by screws 15, extending 85 upward from spherical feet 16, which coact with the feet 9 and the thumb screws 7 in holding the rung 10 above the top surface of the window sill C. The hooks 14 extend loosely through loops 17 upon the bar 4 and after having their curved forward ends 18, 90 which engage the window sill apron C', adjusted into proper relation with the forward ends of the hooks 5, are locked in the loops 17 by set screws 19. 95

It will be understood from the foregoing description that the holder 3 may be adjusted to fit window sills of different sizes, and when it is applied to a window sill it is 100 doubly secured thereto through the intermediacy of the hooks 5 and 14.

In case of a fire the holder 3 is quickly applied to the window sill, after which the ladder 1 is cast from the window. The bracket 2 is then adjusted beneath the ledge 105 of the window to hold the ladder away from the wall of the building, so that a person descending the ladder may readily attain a firm foot hold upon the rungs 2 without having their toes contact the wall of the 110 building.

When the fire escape is not in use the

ladder 1 is wrapped around the holder 3, so that the entire apparatus may be placed in a suit case, or other suitable receptacle.

While I have shown and described the 5 preferred form of my invention, I reserve the right to make such changes in the construction, combination, and arrangement of parts as properly fall within the spirit and scope of the claims.

10 Having thus described my invention, what I claim and desire to secure by Letters Patent, is:

15 1. In a fire escape, a flexible ladder, a bar suitably connected to said ladder, hooks adjustably-engaging said bar and adapted to engage a window sill, means to secure said hooks at any point of their adjustment on the bar, a rung connected to said hooks, and means to space said rung a short distance 20 above the window sill.

2. In a fire escape, a flexible ladder, and a

holder consisting of a pair of L-shaped hooks secured to the ladder and adapted to engage a window sill, means to secure hooks to the window sill, a bar uniting said claw 25 members, a second pair of hooks adjustably-engaging said bar and adapted to engage the window sill and coact with the claw members in supporting the ladder, means to secure said second pair of hooks at any 30 point of their adjustment on the bar, a rung connecting said second pair of hooks, and means on the claw members and the second hooks for spacing the rung a short distance above the window sill. 35

In testimony whereof I affix my signature, in the presence of two witnesses.

JAMES F. SPALDING.
